UNITED STATES PATENT OFFICE.

OSWALD H. HANSEN, OF PORT WASHINGTON, WISCONSIN, ASSIGNOR, BY DIRECT AND MESNE ASSIGNMENTS, TO HANSEN CANNING MACHINERY CORPORATION, A CORPORATION OF WISCONSIN.

STERILIZING APPARATUS.

Application filed February 19, 1921. Serial No. 446,339.

To all whom it may concern:

Be it known that I, OSWALD H. HANSEN, a citizen of the United States, residing at Port Washington, in the county of Ozaukee and State of Wisconsin, have invented a certain new and useful Sterilizing Apparatus, of which the following is a specification.

This invention relates in general to improvements in the art of treating food stuffs in order to preserve the same, and relates more specifically to improved apparatus for automatically cooking and sterilizing foods after they have been packed in containers.

An object of the invention is to provide simple and efficient apparatus for cooking and sterilizing food stuffs which have been packed in containers.

The present invention contemplates the provision of improved automatic cooking apparatus which will operate at a speed commensurate with that of any high speed filler, which will eliminate the human element, in which the operating cost is reduced to a minimum, which is perfectly reliable, which reduces the necessary floor space to a minimum, and in which maximum efficiency of sterilization is attainable. The improved apparatus has the specific advantages over the prior automatic cookers, of permitting gradual heating and cooling of the cans thereby eliminating disruption of the seams, of avoiding necessity of completely disabling the mechanism when one or several cans become jammed, of permitting ready removal of a jammed can, of permitting efficient sterilization of different grades of material, and of permitting sensitive control of the heating agency.

A clear conception of an embodiment of the invention and of the manner of operating mechanism constructed in accordance therewith, may be had by referring to the drawing accompanying and forming a part of this specification, in which like reference characters designate the same or similar parts in the several views.

Fig. 1 is a central vertical section through one form of the improved sterilizing apparatus.

Fig. 2 is a transverse horizontal section through the improved sterilizing apparatus, the section being taken along the line II—II looking in the direction of the arrows. 55

Fig. 3 is a fragmentary central vertical section through the improved sterilizing apparatus, the section being taken along the line III—III looking in the direction of the arrows. 60

The improved automatic cooker and sterilizer comprises in general a main frame 2, an annular series of four or more vertically elongated compartments forming treating chambers 3, 4, 5, 6 which are rotatably supported by the frame 2, a can supply chute 26 for conducting food laden cans 12 to the upper ends of the successive chambers 3, 4, 5, 6, a can stop 33 associated with the supply chute 26, a can discharge chute 27 for conducting the treated cans 12 away from the lower ends of the successive chambers 3, 4, 5, 6, a drip catch or water drain 32 located below and extending laterally of the can discharge chute 27, and power means 65 for intermittently moving the treating compartments to different positions about a central vertical axis. 70

The main frame 2 is provided with vertically spaced upper and lower central hubs 80 within which a tubular bearing member 7 is rigidly secured. Vertically spaced continuous upper guide rails 8 are rigidly attached to the frame 2 adjacent to the upper ends of the chambers 3, 4, 5, 6 and have upwardly distorted portions 10 located adjacent to the can supply chute 26. Vertically spaced continuous lower guide rails 9 are rigidly attached to the frame 2 adjacent to the lower ends of the chambers 3, 4, 5, 6 and have downwardly distorted portions 11 located adjacent to the can discharge chute 27. The water drain 32 is located below and extends along the distorted portions 11. Each of the treating compartments is of sufficient size to confine a plurality of food laden cans 12 disposed one above the other, and is provided with a hinged top cover 15 having an actuating roller 28 which coacts with the upper rails 8. The top covers 15 are provided with vent cocks 34 for permitting escape of gas 90 95 100

from within the chambers 3, 4, 5, 6. Each of the treating compartments is also provided with a hinged lower cover 16 having an actuating roller 29 which coacts with the lower rails 9.

The treating compartments are rigidly united by means of a plurality of radial struts formed integral with the compartments and with a lower bearing coacting 10 with the central tubular member, and by means of a circular top plate having an upper integral bearing likewise coacting with the central tubular member 7. The lower radial struts are provided with steam supply conduits or passages 30 which are automatically and periodically connected to the main steam inlet 13 through a transverse opening in the tubular member 7 located directly below a partition in the member 7 as 15 shown in Fig. 2, during rotation of the treating compartments. The upper radial struts are provided with water supply conduits or passages 31 which are automatically and periodically connected to the main water 20 inlet 14 through a transverse opening in the tubular member 7 located directly above the partition in the member 7 as shown in Fig. 3, during rotation of the treating compartments. The lower bearing 25 is provided with a stuffing box 35 for preventing escape of fluid under pressure along the exterior surface of the tubular member 7.

The power apparatus for intermittently moving the treating chambers 3, 4, 5, 6 to 30 different positions about the axis of the tubular member 7, comprises a main horizontal power shaft 22 rotatably supported upon the frame 2, a worm gear 21 secured to a medial portion of the shaft 22, a vertical column or stub shaft 19 secured to the frame 2, a worm wheel 20 rotatable upon the shaft 19 and meshing with the worm gear 21, and Geneva gearing drivingly connecting the worm wheel 20 with the lower bearing of the 35 treating compartments. Associated with an end of the power shaft 22 are idler and driving pulleys 24, 23 respectively, with either of which a drive belt 25 may be made to coact. The Geneva gearing consists of 40 a driving member 18 secured directly to the worm wheel 20 and having a driving roller 36 revoluble about the axis of the shaft 19, and a radially slotted driven member 17 engageable with the member 18 and roller 36, the member 17 being rigidly secured to the 45 lower compartment bearing. This Geneva gearing is a well known mechanical movement and is adapted to transmit intermittent rotary movement to the treating compartments from the continuously rotating power shaft 22.

During normal operation of the apparatus, the driving belt 25 is brought into coaction with the drive pulley 23 thus imparting rotary motion to the shaft 22 and to

the worm gear 21. The rotating worm 21 produces relatively slow rotation of the worm wheel 20 and of the gear member 18 about the axis of the stub shaft 19. As the gear member 18 revolves the roller 36, intermittent rotary motion is imparted to the gear member 17 thereby causing the chambers 3, 4, 5, 6 to alternately revolve through 90 degree arcs and to stop for predetermined definite periods of time. As the successive chambers 3, 4, 5, 6 approach the can supply chute 26, the rollers 28 carried by the top covers 15 ride up the rail portions 10 and automatically open the covers 15 as indicated in Fig. 3. The food laden cans 12 resting upon the chute 26 and held against endwise movement by the stops 33, are released by virtue of the open cover 15 and are then free to roll along the chute 26 and drop by gravity into the successive open chambers 3, 4, 5, 6 as these chambers are held stationary in alinement with the chute 26 by the Geneva gearing. From filling position, the successive loaded chambers 3, 4, 5, 6 are advanced to the position in which chamber 3 is shown in Figs. 1 and 2, whereupon the top covers 15 are automatically sealed and steam is automatically gradually admitted from the main steam inlet 13 through the passages 30 to the interiors of the treating chambers. When steam is thus admitted to a stationary treating chamber the vent cock 34 is opened momentarily, thus producing a rapid flow of steam into the chamber, the temperature, pressure and rate of flow of the steam being regulated by means of an automatic regulator associated with the inlet 13. The successive heated chambers 3, 4, 5, 6 are subsequently advanced to the position in which chamber 4 is shown in Figs. 2 and 3, whereupon a cooling agent such as water is automatically gradually admitted from the main cooling fluid inlet 14 through the passages 31 to the interiors of the treating chambers. The temperature and flow of the cooling fluid are controlled by means of an automatic regulator to produce gradual cooling of the treated cans 12. The successive cooled chambers are subsequently advanced to the position in which chamber 5 is shown in Figs. 1 and 2 whereupon the cans 12 are discharged by gravity and delivered in succession down the discharge chute 27. As the chambers advance toward the discharge position the rollers 29 carried by the bottom covers 16 ride down the rail portions 11 and automatically open the covers 16 as indicated in Fig. 1. When the bottom covers begin to open the water from the treating chambers is precipitated into the water drain 32 by the aid of which such water is conducted away from the apparatus. The successive empty chambers 3, 4, 5, 6 are subsequently presented to the can supply chute 120

26 whereupon the cycle of operations is repeated.

It will thus be noted that the successive food laden cans 12 are automatically sterilized, cooled and delivered, thereby entirely eliminating manual handling of the same. The rate of treatment may be altered to conform with the rate of delivery of the filled cans 12 from the closing machines, 10 either by varying the speed of the drive shaft 22, by increasing the number of chambers 3, 4, 5, 6 or by providing several sterilizers for each filling machine. The necessity of manually transporting the food laden cans 12 from the closing machines to the sterilizer, from the sterilizer to the cooling bath and from the cooling bath to a subsequent destination, is entirely eliminated. The operation of the vent cocks 34 may 20 readily be made automatic thereby permitting the closing machine operator to assume complete control of the sterilizers as well, without undue effort, and reducing the cost of operation to a minimum. The individual 25 compartments may be made of sufficient size to receive any desired number of cans 12 and the number of cans 12 actually admitted to each chamber 3, 4, 5, 6 may be limited as is desirable when there are a limited number 30 of cans 12 packed with a grade of material requiring treatment for special periods of time. The degree of sterilization may be readily varied to suit the characteristics of the particular product confined in each 35 chamber thereby permitting most efficient treatment of the product. The elimination of crates and other transporting apparatus reduces to a minimum the necessary floor space and permits disposition of the sterilizer relatively near to the packing apparatus. 40

In the event that one or more cans 12 become jammed in one of the chambers 3, 4, 5, 6, the remaining chambers are still available for the treatment of product. The 45 jammed can may be readily removed by merely removing the roller 28 and raising the cover 15 of the disabled compartment. The waste of heating and cooling agencies is reduced to a minimum by closely confining the cans 12, and the temperature pressure and rate of admission of these agencies may be effectively controlled with the aid of reliable regulators. The heating and cooling 50 operations may thus be conducted as gradually as necessary in order to avoid disruption of the can seams and consequent spoilage of product.

The apparatus as disclosed in the drawing, is illustrated diagrammatically and in 55 relatively simple and compact form in order to permit clear description of its operation. The Geneva gearing may be replaced by any other mechanism adapted to transport the food product through the successive steps of 60 the cycle of operation, and the sizes and

number of treating chambers 3, 4, 5, 6 may be increased or diminished without departing from the scope of the invention.

It should be understood that it is not desired to limit the invention to the exact 70 details of construction and of operation of the apparatus herein shown and described for various modifications within the scope of the claims may occur to persons skilled in the art.

It is claimed and desired to secure by Letters Patent:—

1. In combination, means forming a chamber, means for automatically confining a plurality of food laden containers within 80 said chamber, means for simultaneously heating all of said confined containers, means for subsequently cooling all of said confined containers, and means for effecting automatic release of said cooled containers 85 from said chamber.

2. In combination, means forming a chamber, means for effecting automatic delivery of a plurality of food laden containers into said chamber, means for automatically sealing said chamber to confine 90 said containers therein, means for simultaneously heating all of said confined containers, means for subsequently cooling all of 95 said confined containers, and means for subsequently automatically unsealing said chamber to permit discharge of said containers.

3. In combination, means forming a chamber, means for automatically confining a plurality of food laden containers within 100 said chamber, means for moving said chamber about an axis, means for successively heating and cooling all of said confined containers at different points in the advancement of said chamber, and means for subsequently effecting automatic release of said containers from said chamber.

4. In combination, means forming a 110 chamber, means for intermittently moving and stopping said chamber, means for automatically confining a plurality of food laden containers within said chamber while stopped, means for simultaneously heating all of said confined containers while said chamber is subsequently stopped, means for cooling all of said confined containers while said chamber is subsequently stopped, and means for effecting automatic release of 115 said containers while said chamber is subsequently stopped.

5. In combination, means forming an annular series of chambers, means for confining a plurality of food laden containers within successive chambers of said series, means for simultaneously heating all of the 125 containers confined within one of said chambers, means for subsequently simultaneously cooling all of the confined containers, and means for subsequently effecting automatic 130

- 4
- release of said containers from successive chambers of said series.
6. In combination, means forming an annular series of chambers, means for automatically confining a plurality of food laden containers within successive chambers of said series, means for successively heating the containers confined in successive chambers of said series, means for successively cooling the confined containers, and means for subsequently effecting unsealing of successive chambers of said series whereby discharge of said containers is permitted.
7. In combination, means forming an annular series of chambers, means for automatically confining a plurality of food laden containers within successive chambers of said series, means for heating the containers confined within successive chambers of said series, means for subsequently cooling the containers confined within successive chambers of said series, and means for effecting automatic release of said cooled containers from successive chambers of said series.
8. In combination, means forming an annular series of chambers, means for rotating said chambers about a central axis, and means for automatically opening the upper ends of successive chambers of said series to admit containers thereto and for subsequently automatically opening the lower ends of successive chambers of said series to permit delivery of said containers therefrom.
9. In combination, means forming an annular series of upright chambers, means for intermittently advancing said chambers about a common vertical axis, means admitting food laden containers through the tops of successive chambers of said series, and a pivoted cover for effecting automatic removal of said containers from the bottoms of successive chambers of said series.
10. In combination, means forming an annular series of chambers each having an upper and a lower cover, means for automatically opening the successive covers of said chambers, means for subsequently automatically admitting steam to the successive chambers of successive series, and means for subsequently opening the successive lower covers of said chambers.
11. In combination, means forming an annular series of upright chambers movable about a vertical axis, means for automatically delivering a plurality of food laden containers downwardly to each of said chambers as the same move past a predetermined point, means for subsequently heating the successive chambers of said series, means for subsequently cooling the successive chambers, and means for subsequently automatically removing said containers downwardly from said chambers as they move past a predetermined point.
12. In combination, means forming an annular series of upright chambers, means for intermittently advancing said chambers about a common vertical axis, means for delivering a plurality of food laden containers downwardly to each of said chambers while at rest, means for automatically delivering heating agency to each of said chambers, means for automatically delivering cooling agency to each of said chambers, and means for subsequently automatically removing said containers downwardly from said chambers while at rest.
13. In combination, means forming a plurality of chambers, means for intermittently advancing said chambers about a common axis, means for automatically confining a plurality of food laden containers in each of said chambers while at rest, means for heating said confined containers, means for cooling said confined containers, and means for automatically effecting removal of said containers from successive chambers of said series while at rest.
14. In combination, means forming an annular series of vertically elongated chambers, means for intermittently advancing said chambers about a vertical axis, means for automatically confining a plurality of food laden containers in successive chambers of said series while at rest, means for heating said confined containers while said chambers are at rest, means for cooling said confined containers while said chambers are at rest, and means for automatically effecting removal of said containers from successive chambers of said series while at rest.
15. In combination, means forming an annular series of chambers, a top cover for each of said chambers, a bottom cover for each of said chambers, and means for successively raising and lowering said top and bottom covers.
16. In combination, means forming an annular series of chambers, Geneva gearing for revolving said chambers about an axis, a top cover for each of said chambers, a bottom cover for each of said chambers, and cam rails for opening and closing successive top and bottom covers during movement of said chambers by said Geneva gearing.
17. In combination, an annular series of chambers movable about a vertical axis, means for admitting food laden containers to the upper extremities of successive chambers of said series, means for successively heating and cooling said containers while within said chambers, and means for delivering said containers from the lower extremities of successive chambers of said series.

In testimony whereof, the signature of the inventor is affixed hereto.

OSWALD H. HANSEN.
